TILED CONSTRUCTION

Zeno Charles Wilkinson, Warren, Ohio, assignor
to Porcelain Tile Corporation, Warren, Ohio,
a corporation of Delaware

Application August 5, 1932, Serial No. 627,561

9 Claims. (Cl. 72—18)

This invention relates to the construction of tiled walls and other surfaces, and particularly to means whereby the tiling may be applied in the form of panels or large sections and detachably secured to the supporting structure.

It is common practice to tile the walls of various sorts of retail establishments, lunch-rooms, etc. Heretofore the tiles were applied in situ, thus causing loss of use of the premises while the work was going on, which was particularly serious in the case of expensive quarters. Moreover, the tiles were attached in a permanent manner and thus could not be removed by the tenant upon expiration of the lease.

15 The present invention provides means whereby large panels which are almost completely tiled at a factory, may be secured to the surface to be covered very expeditiously, and in a manner permitting removal when the establishment is to be moved to another location.

20 In the accompanying drawing

Figure 1 is a fragmental front view.

Figure 2 is a vertical section on line 2—2 of Fig. 1.

25 Figs. 3 and 4 are fragmental sectional views on a larger scale than that of Fig. 2.

Fig. 5 is a section on line 5—5 of Fig. 1.

The tiled surface, proper, may be constructed in various ways, and may comprise tiles of various materials and forms. In the present instance I have shown steel-bodied porcelain-enamedled tiles of the type disclosed in the Haines Patents Nos. 1,594,614 and 1,686,812. These tiles are designated A in the drawing, and each comprises a metal plate having marginal flanges 1. The tiles may be of any desired form and dimensions.

30 The tiles A are mounted upon panels. The panels may be constructed in various ways and may be of any convenient size. In the present embodiment of the invention I have employed large rigid sheets 2 of such material as "Nuwood", "Celotex", "Sheetrock", etc. In the illustrative installation represented in the drawing, two sheets suffice for the height of wall W shown, the vertical dimension of the lower sheet being 35 $\frac{3}{4}$ ", and that of the upper sheet being 59 $\frac{3}{4}$ ". The horizontal dimension of each sheet may be such as convenience dictates, as, for example 48".

35 Each sheet is provided with a suitable backing herein shown as consisting of a wooden framework made up of top and bottom bars 3 and 4, end bars 5 and 6 and intermediate horizontal and vertical bars 7 rigidly secured together. The height and length of the wooden framework cor-

responds to the height and length of the sheet 2. The thickness of the framework may be as desired, being herein assumed to be $\frac{1}{8}$ ". The sheet is fastened to the framework with nails 8 or by any other suitable means engaging the backing at 5 relatively frequent intervals. While I have herein shown a wooden framework, it will be understood that a metallic backing may be used, if desired.

The panel composed of the sheet 2 and its supporting framework is covered with tiles A, the latter being secured in place by any preferred means. Herein I have shown the face of the sheet as having grooves 9 to receive the flanges 1 of the tiles, these grooves serving to locate the tiles accurately with relation to one another. 10 denotes a layer or film of cement used to cause the tiles to adhere to the sheet 2, and 11 indicates grouting or pointing material in the spaces between adjacent tiles. As many of the tiles as 20 possible are mounted on the panels at the factory, the remainder being set after the panels have been placed in position on the wall.

While the means for detachably securing the panels to the wall may partake of various forms, 25 I have herein shown means comprising an angle bar 12, one flange of which is attached by screws 13 to the floor F against or adjacent to the wall to be tiled. Inasmuch as the wall may not be quite vertical and plane, it may be desirable to 30 set the angle bar 12 at a slight distance from the wall, as shown in the drawing.

The lower panel is adapted to engage the vertical flange of the bar 12, as by means of a groove 14 extending longitudinally of the bottom 35 edge of the frame-bar 4.

The upper portion of the lower panel is secured to the wall in any preferred manner, as by means of a Z-bar 15, one vertical flange of which is attached to the rear side of the top 40 bar 3 at the upper edge of the latter by screws 16. The other vertical flange of the Z-bar is apertured to receive screws 17 which engage expansion sleeves 18 inserted in openings 19 in the wall. If necessary in order to make the 45 panel vertical, shims of any desired nature may be inserted between the wall and the panel, as, for example, a washer 20 on each of the screws 17.

The upper vertical flange of the Z-bar 15 is herein utilized to hold the lower part of the upper 50 panel in place, the lower edge of the bar 4 of said panel being grooved, as at 21, to fit over said flange. The lower edge of the upper panel is notched, as at 22 to accommodate the screws 17 when the upper panel is being put in place. 55

5 The upper portion of the upper panel is secured in place by means of an angle bar 23 fixed to the upper edge of the panel and attached to the wall by means of screws 24 or the like, a washer 25 being utilized, if necessary, to bring the panel to a vertical plane.

10 After two horizontally aligned panels have been mounted on the wall, the adjoining edges of the panels may, if desired, be connected together by means such as staples 26, the vertical edges of the sheets 2 being notched as at 27, to permit the application of the staples.

15 In practice, the panels are tiled at the factory as nearly completely as possible, tiles being omitted along those edges where fastenings are to be applied, as in the case of the screws 17 and the staples 26. The bar 12 having been secured to the floor, and expansion sleeves 18 having been placed in the wall at proper points, the panels are set in place and secured in position by means of the screws 17 and 24 and staples 26. The remaining tiles are then cemented to the sheets 2 and the spaces between the tiles grouted, thereby concealing the screws 17 and 25 the staples 26.

30 The space between the upper edge of the lower panel and the lower edge of the upper panel is just sufficient to receive the flanges of the tiles and the grouting so as to produce a grouted joint identical in appearance with the joints between other field tiles. Similarly the vertical edges of adjacent panels are tiled and grouted to produce a grouted joint that is uniform in appearance with those between other tiles.

35 The upper edge of the tiled wall surface may be finished in any preferred manner. If the tenant should desire to move the tiling to another location, the tiles that cover the fastenings 17 and 26 are removed, the fastenings withdrawn, and the panels lifted out of engagement with the bars 15 and 12.

40 It will be seen that the system of construction herein disclosed permits much of the work to be done at the factory, thus reducing the time during which operations are carried on at the premises. Moreover, the tiling may be moved to another location with comparatively little loss of material or labor.

45 In certain of the following claims I have used the term "structure" to denote a wall, floor, ceiling or other portion of a building.

I claim as my invention:

50 1. The combination of a floor, a wall, a bar secured to the floor alongside the wall, a lower panel having a groove in its lower edge to receive a flange of said bar, a bar secured to the upper edge of the panel, means for securing the bar to the wall, an upper panel having a groove in its lower edge to receive a flange of the second-mentioned bar, a flange on the upper edge of the upper panel, and means to attach the last-mentioned flange to the wall, the lower edge of the upper panel being recessed to accommodate said securing means.

55 2. The combination of a floor, a wall, a lower panel, means for securing the panel to the floor alongside the wall, a Z-bar secured to the upper edge of the panel, means for securing the Z-bar to the wall, an upper panel having a groove in

its lower edge to receive a flange of the Z-bar, a flange on the upper edge of the upper panel, and means to attach the last-mentioned flange to the wall, the lower edge of the upper panel being recessed to accommodate said securing means.

60 3. The combination of a floor, a wall, a lower panel, means for securing the panel to the floor alongside the wall, a bar secured to the upper edge of the panel, means for securing the bar to the wall, an upper panel having a groove in its lower edge to receive a flange of the bar, means to attach the upper portion of the upper panel to the wall, and a multiplicity of tiles covering each of said panels and concealing said bar.

65 4. The combination of a floor, a wall, a lower panel, means for securing the panel to the floor alongside the wall, a Z-bar secured to the upper edge of the panel, means for securing the Z-bar to the wall, an upper panel having a groove in its lower edge to receive a flange of the Z-bar, and means to attach the upper portion of the upper panel to the wall.

70 5. The combination of a structure, a bar secured alongside the structure, a panel having a groove in one edge to receive a flange of said bar, a bar secured to the opposite edge of the panel, means for securing the second-mentioned bar to the structure, another panel having a groove in one edge to receive a flange of the second-mentioned bar, a flange on the opposite edge of said other panel, and means to attach the last-mentioned flange to the structure.

75 6. The combination of a wall, a bar secured alongside the wall, a lower panel having a groove in its lower edge to receive a flange of said bar, a bar secured to the upper edge of the panel, means for securing the second-mentioned bar to the wall, an upper panel having a groove in its lower edge to receive a flange of the second-mentioned bar, and means to attach the upper portion of the upper panel to the wall.

80 7. The combination of a wall, a bar secured alongside the wall, a panel comprising a backing covered with a multiplicity of tiles, said backing having a groove in its lower edge to receive a flange of said bar, a bar secured to the upper edge of the backing, and means for detachably securing the second-mentioned bar to the wall.

85 8. The combination of a wall, a lower panel, means to secure the lower portion of the panel in proximity to the wall, a bar secured to the upper edge of the panel, means for detachably securing the bar to the wall, an upper panel having a groove in its lower edge to receive a flange of the bar, and means for detachably securing the upper portion of the upper panel to the wall.

90 9. The combination of a wall, a lower panel, means to detachably fix the lower portion of the panel with reference to the wall, an upper panel, means to detachably fix the upper portion of the upper panel with reference to the wall, means to detachably connect the upper edge of the lower panel to the lower edge of the upper panel, and means for detachably connecting the adjacent portions of the panels to the wall.

ZENO CHARLES WILKINSON.
